United States Patent Office

Des. 185,347
Patented June 2, 1959

185,347

COMPOSITE MINNOW TRAP AND BAIT BUCKET OR THE LIKE

Morris Clayton, Cincinnati, Ohio

Application November 14, 1957, Serial No. 48,448

Term of patent 14 years

(Cl. D31—4)

Fig. 1

Fig. 2

Fig. 3

Fig. 1 is a perspective view of a composite minnow trap and bait bucket or the like, showing my new design.

Fig. 2 is a side elevational view thereof, the portion of the side being broken away to show the shape of the end; and

Fig. 3 is a left end elevational view of Fig. 1.

I claim:

The ornamental design for a composite minnow trap and bait bucket or the like, as shown.
